US00D629358S

(12) **United States Design Patent**
Slippy et al.

(10) **Patent No.:** US D629,358 S
(45) **Date of Patent:** ** *Dec. 21, 2010

(54) **ELECTRICAL CONNECTOR**

(75) Inventors: **Gordon Slippy**, Murrysville, PA (US);
Donald E. Hines, Butler, PA (US);
Charles Amurgis, Mars, PA (US); **Jon J. Danzak**, Pittsburgh, PA (US)

(73) Assignee: **Vocollect, Inc.**, Pittsburgh, PA (US)

(**) Term: **14 Years**

(21) Appl. No.: **29/358,324**

(22) Filed: **Mar. 25, 2010**

Related U.S. Application Data

(62) Division of application No. 29/343,217, filed on Sep. 9, 2009, now Pat. No. Des. 615,040.

(57) **CLAIM**

The ornamental design for an electrical connector, as shown and described.

DESCRIPTION

FIG. 1 is a front perspective view of an embodiment of the invention;

FIG. 2 is another perspective view of the invention of FIG. 1;

FIG. 3 is a front elevational view of the invention of FIG. 2; FIG. 4 is a cross-sectional view of the invention along lines 4—4 in FIG. 3;

FIG. 5 is a right side elevational view of FIG. 2, with the left side elevational view being a mirror-image;

FIG. 6 is a rear elevational view of FIG. 2;

FIG. 7 is a top view of FIG. 2; and,

FIG. 8 is a bottom view of FIG. 2.

The broken lines shown in FIGS. 1 and 4 of the Drawings are included for the purpose of illustrating environment structure, and form no part of the claimed design.

1 Claim, 4 Drawing Sheets
